UNITED STATES PATENT OFFICE.

JAMES H. GEORGE, OF NEW YORK, N. Y.

METALLIC BARREL.

1,324,446.

Specification of Letters Patent.

Patented Dec. 9, 1919.

Application filed December 29, 1916. Serial No. 139,472.

To all whom it may concern:

Be it known that I, JAMES H. GEORGE, a citizen of the United States, and a resident of the borough of Manhattan, city, county, and State of New York, have invented a certain new and useful Improvement in Metallic Barrels, of which the following is a specification.

My invention relates to metallic packing and storing vessels designed for the shipment of liquids such as petroleum products, and more particularly to that type of such vessels which may be "knocked down" and the parts nested for transportation when empty.

My object is to provide a knock-down vessel for the shipment of liquids which will be strong and durable in use, will be unbreakable, will be readily knocked down and reassembled and which is composed of a minimum number of parts, and which has few joints.

These and further objects will more fully appear in the following specification and accompanying drawings considered together or separately.

I have illustrated my invention in the following drawings in which like parts are indicated by similar reference characters in all of the several figures, and in which,

Figure 1 is a longitudinal section of a barrel constructed according to my invention.

Fig. 2 is a side elevation of a sealing strip.

Fig. 3 is an edge view of the same.

Fig. 4 is a horizontal section taken on the line 4—4 of Fig. 7.

Fig. 5 is a similar view on the line 5—5 of Fig. 8.

Fig. 6 is a similar view on the line 6—6 of Fig. 7.

Fig. 7 is a section on the line 7—7 of Fig. 6.

Fig. 8 is a section on line 8—8 of Fig. 5, and

Fig. 9 is a sectional view of a modification.

In the embodiment of my invention illustrated I show a bilge barrel composed of two sheet metal staves 1 and 2. The staves are each cut to the proper configuration and formed to the shape of a semi-cylinder with bulged sides. The staves are identical in form.

Along the edge of each stave is a wing 3 and the opposite edge of the stave has a

wing 4. The wings 3 and 4 are of a length less than that of the staves for a purpose to be hereinafter described. The wing 3 of each stave is slotted at intervals to produce 60 tongues 5, and at points corresponding to the tongues slots 6 are cut or otherwise formed at the base of the wing 4. The slots are so proportioned that the tongues 5 of the cooperating stave when bent at right 65 angles to the wing may freely enter them. The wing 3 is bent inwardly at substantially a right angle to the edge of the stave. The tongues 5 are bent inwardly a distance equal to about the thickness of the metal of 70 the barrel and then bent forward on a line parallel to the transverse curve of the stave and lying within the boundary of the stave, a distance at least equal to the thickness of the tongue. The tongues therefore project 75 beyond the edge of the stave and in proximity to the adjoining stave. The wing 4 of each stave is bent inward at approximately a right angle to the edge of the stave.

The ends of the stave are bent inward and 80 then downward to form an annular inturned rim 7 and the inner extremity of the rim is rolled to form a recess or croze 8. The stave is provided near each end with a peripheral groove or recess 9 and the base of 85 the metal displaced to form the groove 9 contacts with the metal displaced to form the recess 8. This construction will effectually prevent the rim 7 from springing outwardly. Additional grooves are formed in 90 the stave as shown at 9^a.

I provide a sealing strip 10 of a yielding material which will not be affected by the contents of the barrel. I have found that asbestos is a material well adapted for this 95 purpose although other materials, animal, vegetable or mineral, may be employed. The strip is preferably cut to the shape shown in Fig. 2 with slots 11 and notches 12. A strip is placed on each wing 3 with the 100 tongues 5 projecting through the slots 11. The extremities of the strip will lie against the edges of the stave and annulus and the notches 12 will coincide with the recesses 8.

A pair of staves formed as above described 105 are assembled with the wing 3 of one stave, carrying the strip 10, in contact with the wing 4 of the other stave, and with the tongues 5 projecting through the slots 6. Body hoops 13 are now driven toward the 110 bilge of the barrel so formed from each end. The hoops are driven down until they cover

the grooves 9. A center punch is now driven into each hoop 13 at intervals thus forcing the material of the hoop into the groove as at 14. The driving of the hoops 5 will draw the staves together and compress the sealing strips to form an unbreakable joint between the staves.

A gasket 15 is now placed in each end of the barrel and rests within the croze 8. This 10 gasket is preferably provided with an interior circumferential groove. A head 16 is now sprung into the groove in the gasket whereby an unbreakable joint is formed between the annular rim of the staves and the 15 head.

In connection with my improved barrel I provide a seamless annular end cap or hoop 17. The end cap or hoop is composed of an outer flange 18 which conforms in shape to 20 the outer contour of the end of the barrel and an inner flange 19. The end cap or hoop is driven on the end of the barrel until the flange 19 contacts with the outer surface of the head 16, and as the flanges 18 25 and 19 have a driving fit with the outer surface of the barrel and the rim 7 respectively, a strong and rigid structure is produced. The engagement of the flange 19 with the inner surface of the extension will 30 cover the joints between the staves and prevent the ends of the sealing strips 10 from being displaced.

In order to prevent accidental displacement of the end cap or hoop a set screw 20 35 may be inserted through the end hoop and engage within the groove 9. The head of the set screw will be flush with the outer surface of the hoop.

In the modification shown in Fig. 9 the 40 upper edge of each stave is turned over to form a flange 21 and the head 22 is in the form of a seamless cup having a cylindrical wall 23 and an outwardly projecting peripheral flange 24. A gasket 25 is placed on the 45 flanges 21 of the staves when the latter are assembled and the flange 24 rests upon the gasket. When the end hoop is driven in place the head will be securely held in position and the gasket will prevent leakage. 50 If desired in the form shown in Fig. 9 the flange 19 of the hoop 17 may be omitted.

The grooves or corrugations 9 and 9^a in addition to the uses above pointed out act 55 to strengthen the barrel and as they are concealed by the hoops 13 and 17 the exterior of the barrel presents an unbroken surface.

When it is desired to pack the barrel for shipment when empty, the set screws 20 are removed and the end hoop driven off. The 60 body hoops 13 are then driven off, the driving force being sufficient to iron out the points 14 made by the center punch. The parts may now be separated and nested for shipment.

65 While I have shown my improved barrel

as composed of two staves, I desire to have it understood that I do not wish to limit myself to such construction and the number of staves may be increased without departing from the spirit or scope of my invention.

70

Instead of using a punch mark to retain the body hoops 13 in position I may employ set screws similar to those shown at 20 for securing the end hoops in place.

In accordance with the provisions of the 75 patent statutes I have described the principle of my invention, together with the apparatus which I now consider to represent the best embodiment thereof, but I desire to have it understood that the apparatus shown 80 is merely illustrative, and that the invention may be carried out in other ways.

Having thus described my invention what I now claim and desire to secure by Letters 85 Patent, is:

1. A knockdown metallic barrel, having a plurality of staves, there being a slotted wing on each stave, a plurality of projecting tongues on each stave, means for securing the staves together with the tongues of one stave engaging the slots in the adjoining stave, a flange on each stave, said flanges forming a cylindrical extension parallel to the longitudinal center of the barrel, said extension being of less diameter 95 than the barrel, there being a croze in the extension, and a cap engaging the staves and extending over and into the extension.

2. A knockdown metallic barrel, having a plurality of staves, there being a slotted 100 wing on each stave, a plurality of projecting tongues on each stave, means for securing the staves together with the tongues of one stave engaging the slots in the adjoining stave, a flange on each stave, said flanges forming a cylindrical extension parallel to the longitudinal center of the barrel, said extension being of less diameter 105 than the barrel, a ledge on the extension, said ledge forming a croze, and a cap engaging the extension and staves.

3. A knockdown metallic barrel, having a plurality of staves, there being a slotted wing on each stave, a plurality of projecting tongues on each stave, means for securing the staves together with the tongues of one stave engaging the slots in the adjoining stave, a flange on each stave, said flanges forming a cylindrical extension parallel to the longitudinal center of the barrel, said extension being of less diameter 110 than the barrel, a ledge on the extension, said ledge forming a croze, and a cap engaging the extension and staves.

4. A knockdown metallic barrel, having a 115 plurality of staves, there being a slotted wing on each stave, a plurality of projecting tongues on each stave, means for securing the staves together with the tongues of one stave engaging the slots in the adjoining 120

115

120

125

130

- ing stave, a flange on each stave, said flanges forming a cylindrical extension parallel to the longitudinal center of the barrel, said extension being of less diameter than the barrel whereby a space is provided between the stave and the extension, a ledge on the extension forming a croze, a gasket carried by the croze, and a cap engaging the staves and extension. 5 70
- 10 5. A knockdown metallic barrel, having a plurality of staves, a wing on one edge of each stave, a plurality of tongues extending from the wing, a wing on the opposite edge of each stave, there being a plurality of slots in the second wing, means for securing the staves together side by side with the tongues of one stave projecting into the slots of the adjoining stave, there being a sealing strip between adjacent wings, said sealing strip having slots through which the tongues project, a flange on each stave, said flanges forming a cylindrical extension parallel to the longitudinal center of the barrel, and of less diameter than the barrel, a ledge on the extension, said ledge forming a croze, a gasket in the croze, and a cap surrounding the end of the barrel, said cap engaging the inside of the extension and engaging the gasket. 20 75
- 25 6. A knockdown metallic barrel, having a plurality of staves, a wing on one edge of each stave, a plurality of tongues extending from the wing, a wing on the opposite edge of each stave, there being a plurality of slots in the second wing, means for securing the staves together side by side with the tongues of one stave projecting into the slots of the adjoining stave, there being a sealing strip between adjacent wings, said sealing strip having slots through which the tongues project, a flange on each stave, said flanges forming a cylindrical extension parallel to the longitudinal center of the barrel, and being spaced from the staves to form a chamber between the staves and extension, a ledge on the extension, said ledge forming a croze, a gasket in the croze, and a cap surrounding the end of the barrel, said cap having an annular flange engaging the extension, covering the joints therein and engaging the gasket. 30 80
- 35 7. A knockdown metallic barrel, having a plurality of staves, a wing on one edge of each stave, a plurality of tongues extending from the wing, a wing on the opposite edge of each stave, there being a plurality of slots in the second wing, means for securing the staves together side by side with the tongues of one stave projecting into the slots of the adjoining stave there being a sealing strip between adjacent wings, said sealing strip having slots through which the tongues project, a flange on each stave, said flanges forming a cylindrical extension parallel to the longitudinal center of the barrel, there being a groove in the extension, forming a croze, a gasket in the base of the groove, and an annular cap engaging the outer surface of the staves, the top, the gasket, and inside of the extension. 40 85
- 45 8. A knockdown metallic barrel, having a plurality of staves, means for securing the staves together at their longitudinal edges, a flange on each stave, said flanges forming a cylindrical extension extending into the barrel and parallel to the longitudinal center thereof, a circumferential ridge formed in the extension, and a circumferential ridge formed in each stave, said latter ridges being in alinement, the stave and extension ridges being in opposition, the ridges of the staves engaging the ridge of the extension. 90
- 50 9. A knockdown metallic barrel, having a plurality of staves, means for securing the staves together at their longitudinal edges, a flange on each stave, said flanges forming a cylindrical extension extending into the barrel and parallel to the longitudinal center thereof, a circumferential ridge formed in the extension, and a circumferential ridge formed in each stave, said latter ridges being in alinement, the ridges of the staves engaging the ridge of the extension, an annular cap engaging the outer surfaces of the staves and covering the grooves formed by the displacement of the material of the staves in the formation of the ridge on the staves, and means for engaging the cap with the groove. 95
- 55 10. A knockdown metallic barrel, having a plurality of staves, means for securing the staves together at their longitudinal edges, a flange on each stave, said flanges forming a cylindrical extension extending into the barrel and parallel to the longitudinal center thereof, a circumferential ridge formed in the extension, and a circumferential ridge formed in each stave, said latter ridges being in alinement, the ridges of the staves engaging the ridge of the extension, an annular cap engaging the outer surfaces of the staves and covering the groove formed by the displacement of the material of the staves in the formation of the ridge on the staves, and a set screw for engaging the cap with the groove. 100
- 60 11. A metallic bilge barrel having its ends turned to form extensions, said extensions being cylindrical and extending in alinement with the longitudinal axis of the barrel, said extensions being adapted to support a head, there being a peripheral displacement in the material of the wall of the barrel, said displacement engaging the extensions. 110 120
- 65 12. A metallic bilge barrel having its ends turned to form extensions, said extensions being cylindrical and extending in alinement with the longitudinal axis of the barrel, said extensions being adapted to support 125 130

1. a head, there being a peripheral displacement in the material of the wall of the barrel, there being a peripheral displacement of the material of the extensions, said displacement engaging the displacement of the wall of the barrel.

13. A knock-down metallic barrel, having a plurality of staves, each stave having a flange along each longitudinal edge thereof, each stave having an inturned portion at each end thereof, said inturned portions forming, when the staves are assembled to form the barrel, a cylindrical extension in axial alinement with the longitudinal axis of the barrel, thereby forming a recess between the staves and the extension, a sealing strip secured between the flanges of adjacent staves, said sealing strip extending into the joint between the sections of the extension, an annular cap or hoop engaging the outside of the barrel and having an extension engaging the inturned portions of the staves and covering the joints between the staves and the sealing strip therein.
14. A knock-down metallic barrel, having

a plurality of staves, each stave having a flange along each longitudinal edge thereof, each stave having an inturned portion at each end thereof, said inturned portions forming, when the staves are assembled to form the barrel, a cylindrical extension in axial alinement with the longitudinal axis of the barrel, thereby forming a recess between the staves and the extension, there being a recess in the inner extremity of the extension adapted to support a head, a gasket in the recess, a sealing strip secured between the flanges of adjacent staves, said sealing strip extending into the joint between the sections of the extension, and an annular hoop engaging the outside of the barrel, extending into the extension, covering the joints and the sealing strips of the extension and engaging the gasket.

This specification signed and witnessed this 28th day of Dec., 1916.

JAMES H. GEORGE.
